UNITED STATES PATENT OFFICE.

WILLIAM ALEXANDER ARCHER, OF TOPEKA, KANSAS.

WELL-SCREEN.

No. 921,837.

Specification of Letters Patent. Patented May 11, 1909.

Application filed September 24, 1908. Serial No. 454,523.

To all whom it may concern:

Be it known that I, WILLIAM ALEXANDER ARCHER, a subject of the King of Great Britain, and a resident of Topeka, in the county 5 of Shawnee and State of Kansas, have invented a new and Improved Well-Screen, of which the following is a full, clear, and exact description.

My invention relates to well screens, my 10 more particular purpose being to produce a kind of screen made of material which lasts a long time when subjected to the action of sand, water and various salts held in solution.

A special object of my invention is to prevent quick-sand, fine grain sand and mud 15 from entering into the well while the water is being pumped, and especially under conditions where the upper level of the water happens to be lowered to a point below the top 20 of the screen, the device meanwhile allowing the free percolation of the water through the material forming the screen.

I have made the discovery that a matting consisting of woven cocoanut fiber, when 25 sunken into a well and properly mounted, permits the free percolation of water through it and at the same time effectively prevents all silt, whether in the shape of fine grain sand or of quick-sand, from entering the well. 30 It even keeps out of the well mud which would easily pass through the meshes of almost any other screen. Moreover, a well screen made in this manner is practically indestructible and seems to be particularly immune 35 from the deleterious influences which cause so many other screens to become useless.

Reference is to be had to the accompanying drawing forming a part of this specification, 40 in which similar characters of reference indicate corresponding parts in both the figures.

Figure 1 is a vertical section through a 45 drilled well provided with my improved well screen which extends a little distance below the lower end of the tubular casing; and Fig. 2 is an enlarged view, partly in section and partly in elevation, showing how the matting is mounted upon a perforated tube so as to 50 form the screen.

The ground is shown at 3 and may be formed in part of strata 4, 5, 6, of loose material, such as sand, mud and gravel, through which the water finds its way.

At 7 is a pipe which is sunken into the 55 ground by any suitable means, for instance, by first drilling the hole and then lowering the pipe into it. In some instances the pipe may be driven, and in others it may be let down into the drilled hole. 60

A tube 8 is connected at its lower end with a metallic cylinder 9 having perforations 10, and this cylinder is closed at its bottom by a band 11 and cap 12 screwed into the band and against the lower end of the cylinder 9. 65

At 13 is a matting made of woven cocoanut fiber and provided with selvages 14. The matting is wrapped in cylindrical form directly around the cylinder 9 and the two selvages 14 brought into proximity to each 70 other and laced by aid of ligaments 15 of raw hide, leather, cord or wire.

The cylinder 9 and screen 13 should extend a little distance below the lower end of the pipe 7. This is very conveniently done in a 75 drilled well by first sinking the pipe 7 to the bottom, then lowering the tube 8 with the screen at its bottom, and next raising the pipe 7 until its lower end approximates the level of the top of the screen. Water now 80 percolates through the strata 4, 5, 6 and through the cocoanut matting, passing into the cylinder 9 through the perforations 10.

The sand, gravel and other loose material at the bottom of the well are in direct 85 engagement with the cocoanut matting, for the reason that when the pipe 7 is first lifted off the bottom of the well, so as to expose the matting, the sand, gravel and other loose material roll up against the latter and the 90 water swells the matting so as to close its interstices against the entrance of sand. The cocoanut matting, when swollen in this way, makes an ideal screen for the reason that, owing to this swelling, the finest grain 95 of sand is prevented from entering the well, and yet the water may enter freely, owing to the highly porous nature of the matting.

Cocoanut fiber in water is practically imperishable. Being a vegetable product, it is 100 not corrosive in the sense that metallic substances are corrosive when exposed to the action of mineral salts in the ground.

Having thus described my invention, I claim as new and desire to secure by Letters 105 Patent:

1. In a well screen, the combination of a foraminous cylindrical member, and a mat-

ting encircling the same, said matting being provided with selvages and with holes through said selvages, and lacing members extending through said holes for the purpose of drawing said selvages together.

2. In a well screen, the combination of a foraminous cylindrical member and a matting of porous material disposed generally in the form of a cylinder and encircling said 10 first-mentioned member, said matting being provided with edges disposed adjacent to each other, and means for drawing said edges together.

3. In a well screen, the combination of a 15 matting of cocoanut fiber provided

edges, and means for drawing said edges toward each other.

4. In a well screen, the combination of a matting provided with edges and means for drawing said edges toward each other, and 20 means for retaining the matting in cylindrical form for the purpose set forth.

In testimony whereof I have signed my name to this specification in the presence of two subscribing witnesses.

WILLIAM ALEXANDER ARCHER.
